PIANO CONSTRUCTION

Melvin E. Johnson, Chicago, Ill., assignor to P. A. Starck
Piano Co., Chicago, Ill., a corporation of Illinois
Filed June 2, 1964, Ser. No. 371,933
4 Claims. (Cl. 84—177)

This invention relates to improved structures for pianos, particularly upright pianos of the spinet variety, and more specifically is concerned with a new and improved key bottom frame and key bed support means and the combination thereof with the upright piano back in such a manner as to provide a unitary substructure to which the external casing elements and portions of the piano housing may be removably attached.

According to conventional manufacturing practice, upright pianos are usually constructed in such a manner that the supporting structure for the key bed and related elements, constituting a key bottom frame, is attached at its ends and supported directly on the side arms of the piano housing or finished external casing. The side arms in turn usually are affixed to the opposite ends of the upright piano back structure. Such an assembly procedure therefore demands the finished side arms to be included as active supporting elements for the piano back and key bottom support when assembling such members. Consequently, in the normal order of events of conventional piano manufacturing procedure, a completely finished piano including all of the highly polished and finished external casing or housing members is produced on the assembly line and then placed in warehouse storage awaiting shipment to retail outlets and customers. This requires great care and precaution to be taken in order to protect the external housing to avoid marring or scarring thereof while the piano is warehoused. This is quite difficult to accomplish and often results in a material economic loss to the manufacturer over a year's production many times necessitating refinishing of the finished housing surfaces prior to shipment to the customer.

In general, the present invention seeks to avoid the above-outlined difficulties by providing a new and improved subassembly comprising a unitary combination of the upright piano back for a spinet piano or the like, and a new and improved key bottom support and key bed on which the piano keys and action mechanisms are supported. This unitary combination is completely independent of the external housing or casing members and is completed as an integral subassembled unit without reference to the particulars of the decorative housing members which are subsequently applied thereto. By this means, the external housing members may be finished and stored in a protective container independently of the internals of the piano and applied to the subassembled unit of this invention by the manufacturer just prior to shipment of the finished piano product. Thus the hazard of storing the completely finished piano previously experienced is successfully avoided according to one important feature of this invention.

Of equal importance is the new, improved structural arrangement for supporting the key members according to this invention. According to prior practice in this art, the key members and action mechanisms are usually supported on an underlying laminated wood structure or "key bed" which is disposed generally horizontally in front of the piano back and carried either by end brackets attached to the piano back or more commonly by the side arm members of the piano casing as previously mentioned. The provision of the heavy undersupporting wooden structure gives rise to recognized difficulty in maintaining proper adjustment of the keys and action mechanisms due

2

to the natural tendency of the wood undersupport to grow and shrink in accordance with changes of ambient temperature and humidity. This has been a recognized and constant source of difficulty in piano structures for a great many years and so far as I am aware has heretofore presented a vexatious and unresolved problem in the piano art.

According to the present invention, the now familiar heavy wooden key bed is entirely eliminated and the key members are directly supported on an improved rigid key bottom support or frame which constitutes an open metal structure having integral extensions at its opposite ends by which the framework is cantilever connected to the end or upright posts of the piano back. This structure is rigid, stable and provides a completely accurate and static platform for the action mechanisms and piano keys in avoidance of the heretofore vexatious problems experienced with wooden key bottoms or key beds.

Of added importance and advantage is the provision, according to this invention, of an acoustic cloth barrier and dust shield between the piano key assembly and the metal key bottom frame which undersupports the same. This feature produces an improved acoustic characteristic for the piano instrument. The prior practice of employing the solid wooden key beds, as above noted, served to generally block off the escape of sound from the sounding board of the piano through the front of the piano, thereby materially muting the forward sound output of the instrument. With the improved structural arrangement of the present invention, sound readily may escape through the key bottom support frame, and more particularly through the porous acoustic barrier provided to perceptably increase the volumetric output of sound adjacent the frontal regions of the piano; the arrangement in effect permitting the passage of sound through the key bed.

Of still further importance in the structural improvements afforded by the present invention is the provision of new and improved mounting means for attaching the front corner legs of the piano directly to the key bottom support frame, with such leg support means comprising an integral, rigid portion of the key bottom support frame.

The main object of the present invention is to provide a new and improved construction for a piano whereby an independent and integral unit is achieved for mounting the active instrument elements without reference to the particulars of the exterior housing or decorative casing therefor.

Another important object of this invention is to provide a new and improved piano construction as aforesaid in which a novel unitary metal key bottom support frame is provided which is characterized by improved stability and rigidity so as to promote the operational regulation of the key members and action mechanisms.

A still further important object of this invention is to provide a new and improved combined piano back and key bottom support assembly which provides an effective key bed capable of permitting the ready escape of sound through the front of the piano instrument.

Still an additional object of this invention is to provide a simplified unitary piano assembly including an improved key bottom support means which is characteristically productive of improved manufacturing economies and which may be assembled independently of the external housing or casing of the instrument.

A still further object of this invention is to provide new and improved means for undersupporting the key members and action mechanisms of an upright piano which includes improved means for affixing the forward supporting piano legs directly thereto.

The above and further objects, features and advan-

tages of this invention will be recognized by those familiar with the art from the following detailed description of a preferred embodiment thereof which is exemplified in the accompanying drawings.

In the drawings:

FIGURE 1 is a perspective showing of the improved unitary combination of piano back and key bottom support frame of this invention;

FIGURE 2 is a partial enlarged top plan view of the improved key bottom support frame seen in FIGURE 1;

FIGURE 3 is a partial enlarged cross-sectional view taken substantially along vantage lines 3—3 of FIGURE 1 to show structural details of the improved key bottom support frame; and

FIGURE 4 is another partial enlarged cross-sectional view taken substantially at vantage line 4—4 of FIGURE 2 and looking in the direction of the arrows thereon to illustrate additional structural details of the support frame of this invention.

Having thus described the present invention, the best mode presently contemplated for carrying out this invention and to enable those skilled in the art to practice the same will now be described in detail in relation with the presently preferred embodiment thereof illustrated in the accompanying drawings.

Referring to FIGURE 1 of the drawings, it will be recognized that the unitary assembly, indicated generally by numeral 10 therein, comprises a conventional upright piano back assembly indicated generally by numeral 11, combined with the improved key bottom support frame assembly indicated generally by numeral 12.

While the details and particulars of the piano back structure or assembly 11 will not be described herein because the same is well known to those versed in this art, generally such includes a rather massive wooden structure in the form of a rectangular framework having upright end rails or posts 15, 15 interjoined by the top and bottom of frame rails 16 and 17, respectively. Such framework rigidly supports the usual sounding board, indicated generally at 18. A string plate, indicated schematically at numeral 19 and comprising a generally heavy metal casting, is provided forwardly of the sounding board 18, such carrying the usual strip pins 20, between which the sound producing strings 21 are trained in conventional fashion. It will be appreciated that for purposes of the present disclosure, the illustrated piano back is typical of the type employed in the modern-day spinet piano.

Mounted to project forwardly of the piano back assembly 11 and at an appropriate vertical distance from the floor level is the improved key bottom frame and key bed assembly 12 of this invention. As noted heretofore, frame assembly 12 generally comprises a substantially rectangular rigid framework which is disposed in a plane generally transverse to the general vertical plane of the piano back. In greater detail, the improved frame 12, as seen in FIGURES 1 and 2 of the drawings, includes a pair of cantilever mounting arms 30, preferably formed as solid metal bars of substantially rectangular cross section as shown best in FIGURE 4. Arms 30, 30 are adapted to be fixed in place by screw members 31, 31, or the like, which threadingly engage the end rails 15, 15 of the piano back; such end rails 15, 15 being suitably grooved or cut away to matingly receive the cross-sectional dimension of the arms 30. In this manner, each of the arms 30 for the frame 12 provides a cantilever support system rigidly affixed to the end rails of the piano back and extending forwardly of the piano back 11, as illustrated in FIGURES 1 and 3 of the drawings. With particular regard to the arms 30, it will be appreciated that while the screw members or fasteners 31 hold the same rigidly to the end rail members 15, 15 of the piano back, the provision of the cut-out slot for matingly receiving such arms 30 adds additional strength, rigidity

and support, substantially preventing the same from moving relative to the piano back, particularly with turning movement.

Extending between the two projecting cantilever mounting arms 30, 30 are at least two longitudinal rails or frame members comprising a front frame member 32 and a back frame member 33. Frame members 32 and 33, like the cantilever arms 30, 30 are preferably solid metal bars of substantially rectangular cross-section, and such members are rigidly affixed at their ends to the arms 30, 30 as by welding or like interconnecting means. Extending transversely between the front and back frame members 32 and 33, respectively, are a plurality of four, in the particular embodiment shown, transverse frame members, designated 34, 35, 36 and 37 in FIGURE 2. Such transverse frame members 34-37 are, as best illustrated in FIGURE 4 of the drawings, preferably hollow tubular members of substantially square cross-sectional configuration and of a vertical dimension matching the vertical dimensions of the support arms 30 and front and back frame members 32, 33. This, then, affords a substantially uniform platform thickness for the entire key bottom frame assembly 12.

Each of the transverse frame members 34-37 is welded or otherwise rigidly affixed at its opposite ends to the two frame members 32 and 33. To complete the framework, as illustrated in FIGURES 2 and 4 of the drawings, short support bars 38, 38 are provided between the mounting arms 30, 30 and the adjacent transverse support frame members 34 and 37. The provision of such frame members 38, 38 serves to particularly rigidify the key bottom support frame adjacent the front corners thereof at which the improved means 39 for attaching the front piano legs 40 (see FIGURE 3) are mounted.

As best shown in FIGURES 2, 3 and 4 of the drawings, the means 39 for mounting the piano legs 40 to the frame assembly 12 comprise a pair of planar mounting plates, one located at each of the forward corners of the frame assembly 12 at the junctions of the front frame member 32 and the two mounting arms 30, 30 thereof. Each of the plate means 39 is preferably welded or otherwise rigidly affixed to the respectively adjacent frame members 30 and 32, and each thereof is provided with a pair of openings 42 and 43. Opening 42 is disposed substantially centrally of the herein shown square plate means and is threaded for reception of a mounting stud 44 extending axially out of the upper end of a piano leg 40, whereby the latter readily may be attached to the mounting means 39. Once the mounting stud 44 is fully received and tightened in the opening 42 of its associated mounting means, as illustrated in FIGURE 3, an offset locking screw 45 is then driven downwardly through opening 43 in the mounting means 39 to "keep" the piano leg in its mounted position.

From the foregoing it will be understood that the key bottom support frame assembly 12 constitutes a substantially rigid open framework adapted for cantilever suspension from and in front of the piano back to provide a unitary combination or subassembly, as illustrated in FIGURE 1 of the drawings. It will also be recognized that the above-described key bottom support frame or assembly 12 is readily adapted to receive and under-support the assembled piano keys 50 and the several related action mechanism 51 (see FIGURE 3). Prior to the assembly of the piano keys and action mechanism on frame assembly 12, however, the upper side of such frame is covered over with a unique acoustic barrier and dust shield, indicated generally at numeral 52 in FIGURES 1 and 3 of the drawings. Preferably shield 52 comprises a pervious cloth which is stretched tightly across the frame 12 and attached to the several frame members thereof. After mounting the acoustic cloth in place the assembled piano keys 50 comprising individual key members 55, the usual front rail 56, balance rail 57 and back rail 58 integrated on base means 59 is mounted

on top of the frame assembly 12. It will be noted specifically that the balance rail 57 is aligned substantially over the short frame members 38, 38 while the front rail 56 is affixed over the front frame member 32 of the undersupporting key bottom frame. The piano key assembly is fixed in place by suitable screw fasteners or the like passing through the transverse rail or frame members, particularly members 34-36 and the front frame member 32 of the frame assembly 12.

In a similar manner, the various action mechanisms, indicated generally at 51 in FIGURE 3, are assembled on top of the undersupporting frame 12 so as to engage the strings 21, 21 of the piano back assembly, all in conventional known fashion.

It will be recognized from the foregoing description that the provision of the barrier cloth 52 serves to adequately protect the keys and action mechanisms from dust and the like, while at the same time providing an acoustic shield capable of permitting the escape of sound from the sounding board of the piano back outwardly through the regions adjacent and beneath the piano keys. In effect, a sound path is provided through the open key bed afforded by the key bottom support frame 12 of this invention. In practice, the provision of this type of construction has demonstrated a remarkably improved acoustic characteristic for the finished instrument.

As will be readily understood by those familiar with the art, the combined piano back and key bottom support frame of this invention, as hereinabove described, affords a remarkably compact and unitary subassembly which is capable of receiving all of the active parts of the piano instrument independent of the external piano casing or housing, which therefore are conveniently assembled just prior to shipment of the instrument to the manufacturer's customers. In this respect, it will be readily appreciated that the undersupporting structure for the key assembly and action mechanisms, afforded by the improved key bottom support frame 12, is independent of any of the external housing members of the finished piano instrument, and that the entire support therefor is afforded by the cantilever connection of such frame with the piano back (see FIGURE 1 of the drawings).

It will also be understood that attachment of the end or side arms (not illustrated) to the piano back is brought about in the usual conventional manner, by providing milled-out slots in the inner faces of the side arms receptive of the enlarged head portions of one or more attachment screws 60, 60 projecting outwardly of the end of upright posts 15 of the piano back structure, as indicated in FIGURE 1. In practice, the provision of the rigid metal framework 12 substantially avoids the heretofore experienced difficulty in maintaining proper adjustment for the key assemblies and action mechanisms which has resulted by the previous practice of utilizing a wooden key bottom frame and key bed. With the improved combination of this invention and especially the provision of the improved rigid key bed support afforded by the open frame assembly 12, a completely stable and rigid platform for undersupporting the key assemblies and action mechanisms is provided whereby the instrument's working elements may be assembled by the manufacturer and the action mechanisms and keys properly mounted and adjusted with little or no need for later adjustment. Further, it has been found that the piano back and key bottom support frame combination of this invention may be independently assembled at the factory and placed in storage as a unit for the later addition thereto of selected outer housing or cabinet members. Since the cabinet parts are usually highly finished and susceptible to damage if warehoused in a fully assembled condition, the present invention successfully avoids such storage problem. Thus, the objective and advantage of avoiding the heretofore experienced problem of the manufacturer in maintaining undamaged instruments in warehouse storage is successfully avoided according to the teachings and concepts of this invention.

While the present invention has been described above in association with a particular embodiment of its principles and concepts, it will nevertheless be readily recognized, understood and appreciated by those familiar with the art that numerous changes, modifications and substitutions of equivalents may be made in the described embodiment without necessarily departing from the spirit and scope of this invention. Therefore, it is intended that this invention be unlimited by the foregoing description, except as it may appear in the following appended claims.

I claim:

1. For use in an upright piano the combination comprising, a piano back assembly operationally positioned generally upright and comprising a substantially rectangular frame assembly having upright end rails or posts, a combination key bottom support frame and key bed assembly extending transversely to and in front of said piano back assembly and comprising an open, rectangular metal framework having parallel elongated linear front and back frame members adapted to extend the length of said piano back and linear mounting arms affixed transversely to the opposite ends of said front and back frame members, said arms having integral portions projecting rearwardly of said back frame member and adapted for cantilever attachment transversely to the end posts of the piano back, each of said end posts having a channel cut transversely thereacross and extending inwardly of the outside end face thereof for matingly receiving a said mounting arm portion therein; and fastener means affixing said arm portions to said end posts and preventing the removal thereof from said channels, said key bottom support frame being adapted to undersupport assembled keys and action mechanisms directly thereon and said combined piano back and key bottom support being structurally independent of but adapted to support the exterior piano casing members.

2. The combination as set forth in claim 1 including a pair of mounting plate means affixed to the forward corners of said key bottom support frame and each having means for affixing a piano leg directly to said key bottom support frame.

3. In a piano having an upright piano back assembly including a generally rectangular framework having upright end posts, a sounding board mounted on said framework and string frame means and strings mounted over said sounding board, an improved key bottom support frame mounted transversely of said piano back and extending longitudinally in front of said string frame means and strings comprising, an open rectangular metal framework having parallel spaced front and back linear frame members, a plurality of transverse linear frame members extending between and affixed at their opposite ends to said front and back frame members, and a pair of parallel spaced linear end frame members affixed to and across opposite ends of said front and back frame members and comprising cantilever mounting arms extending rearwardly of said back frame member for attachment to and across the outer end faces of said piano back end posts whereby to position said support frame substantially horizontally in front of said piano back and transversely thereto; said support frame members being fixedly interconnected to form a substantially rigid, stable platform for mounting piano keys and action mechanisms directly thereon, and barrier means mounted across said support frame and between the same and said piano keys and action mechanisms mounted thereon comprising a sound pervious cloth active as a dust barrier and adapted to permit the passage of sound therethrough whereby sound emanating from said sounding board may escape forwardly therefrom through said open key bottom support frame.

4. In an upright piano having a generally upright rectangular piano back assembly including upright end posts, an improved key bottom support frame comprising a generally rectangular open metal framework fabricated of

rigid linear metal frame members rigidly interconnected, said support frame having cantilever mounting arms at its opposite ends and extending rearwardly thereof whereby the support frame may be mounted generally transverse to the general plane of said piano back and longitudinally across the front thereof, said cantilever mounting arms being adapted for connection to and transversely across the upright end posts of said piano back; a barrier cloth mounted over the upper face of said support frame and adapted to shield piano keys and action mechanisms, which are adapted to be mounted thereover and attached to said frame, from dust while permitting the passage of sound therethrough; and means at the forward corners of said support frame for affixing upright piano legs

thereto and comprising a pair of metal plates affixed to the said bottom support frame and having means for effecting the attachment of the upper ends of the piano legs thereto and additional means for locking said piano legs to said mounting means.
